CLAIM

The ornamental design for a shoe outsole bottom as shown and described.

DESCRIPTION

FIG. 1 is a front perspective view of a shoe outsole bottom in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines shown in the drawing represent environmental structure in the form of the shoe midsole periphery and shoe upper as well as portions of the shoe outsole bottom that form no part of the claimed design.
